UNITED STATES PATENT OFFICE.

GEORGE B. DRYDEN, OF CHICAGO, ILLINOIS.

DESIGN FOR AN ELASTIC VEHICLE-TIRE.

SPECIFICATION forming part of Design No. 30,417, dated March 28, 1899.

Application filed March 2, 1899. Serial No. 707,535. Term of patent 7 years.

To all whom it may concern:

Be it known that I, GEORGE B. DRYDEN, a citizen of the United States, residing at Chicago, in the county of Cook and State of Illinois, have invented and produced a new and original Design or Useful Shape for an Elastic Vehicle-Tire, of which the following, in connection with the accompanying drawings, is a full, clear, and exact specification.

10 In the said drawings, Figure 1 is a side elevation of a vehicle-tire embodying my design; and Fig. 2 is an enlarged transverse section thereof, taken on the line 2 2, Fig. 1.

The leading features of my design consist 15 of a tire having formed on its inner side an inwardly-projecting bead or rib A and the flat shoulders B, located at each side thereof. The outer side or tread portion of the body of the tire C is shaped in cross-section like the 20 smaller end of an egg, gradually widening to

the points x, where its diameter again begins to decrease on a gradual curve until the flat shoulders B are reached. These shoulders B are of substantially equal width, and the rib A, which is rounded or semicylindrical, is located at a point midway between them and directly under the apex c of the tire-body, and in line with this apex and the center of the rib A and at a point substantially level with the points x is formed a perforation or round 25 channel D.

Having thus described my invention, what I claim as new therein, and desire to secure by Letters Patent, is—

The design for an elastic vehicle-tire substantially as herein shown and described.

GEO. B. DRYDEN.
